UNITED STATES PATENT OFFICE.

HALVOR E. ANDERSON, OF KENOSHA, WISCONSIN.

DOORCHECK.

Application filed January 28, 1926. Serial No. 84,339.

My invention relates to door fasteners and has for its principal object to provide a device of this character especially adapted for use on doors not provided with a retaining 5 latch and which will normally secure the door against movement in either an open or closed position.

A further object is to provide means operable by the door knob for releasing the 10 gripping jaws, which constitute the fastening means, so as to permit the free opening and closing of the door.

Another object is to provide a device of 15 this character which will automatically cause the door to stop swinging as soon as the knob is released.

Other objects and advantages will become apparent from the following detailed description when viewed together with the 20 accompanying drawings forming part hereof in which—

Figure 1 is an elevational view of a door to which my invention is shown attached.

Figure 2 is an enlarged detail view illustrating the relative position of the gripping jaws with respect to the other features of 25 the device.

Figure 3 is a top plan view.

Figure 4 is a section taken on a line 4—4 30 of Figure 3.

Figure 5 is a top plan view of the jaw supporting bracket and

Figure 6 is a longitudinal sectional view of one of the jaw members and showing the 35 position of the friction block.

Referring now to the drawings it will be seen that I have disclosed my invention as comprising a bracket 5 secured to the outside of a door 6 along the upper edge thereof. Said bracket includes a horizontal shelf 7 having an upturned outer flange 8 and a rib 9 struck up therefrom, each being provided with an aligned opening 10 near one end. A jaw 11 is disposed upon said shelf 40 having side flanges 12 which are arranged to extend downwardly on the outside of the flange and rib on said shelf. The flanges 12 also have an aligned opening and a pin 13 is provided for inserting in said openings whereby to form a pivoted connection 45 between the jaw and the shelf.

The jaw and the shelf are also provided with an aligned opening through which a bolt 14 is vertically disposed and upon the 50 lower end thereof I provide a spiral spring 15 which has its upper end bearing against

the under side of said shelf and its lower end secured by a nut 16. Thus the jaw is normally held downwardly upon the shelf.

A lever 17 is provided having one end 18 60 bent substantially at right angles thereto and which end is inserted transversely between the jaw and the shelf, notches 19 being formed on the flanges carried thereon for clearance within which the bent portion 65 of the lever is adapted to rest, and the end thereof is fitted in an opening provided in a lug 20 which is struck up from the shelf. The bent end of the lever is provided with a raised section 21 which normally engages 70 the under side of the jaw, and a second downwardly bent section 21' the recess formed by which is adapted to engage the flange 12. The other end of the lever has attached thereto a cord 22 which is fastened 75 to an extension 23 fixedly mounted for rotation upon a door knob 23'. The lever is inclined upwardly from its point of attachment between the jaw and the shelf so that a turning of the knob will cause a downward pull on the lever and an upward push 80 of the raised section 21 against the jaw thus causing the jaw to open. The jaws may be locked in open position by a continued downward pull on the lever until the raised 85 section 21 has been moved beyond its highest elevation whereupon the downwardly bent section 21' will be moved against the flange 12 and prevent the closing of the jaws until the movement of the lever is reversed. 90

A semi-circular arm 24 formed of thin metal is attached at one end to the outside of the house adjacent the door frame and the other end is attached to the top of the door 95 frame immediately above the outer end of the jaw so that the arm may be received between the jaw and the shelf, the curvature of the arm being similar to the curve defined by the jaw as the door is swung open or 100 closed.

A pair of friction blocks 25, preferably of hard wood, are secured within the ends of the jaw and shelf, and arranged to engage the upper and lower faces of said arm. 105 Lugs 26 struck up from the jaw and the shelf provide means for retaining the blocks in position. The tension of the spring normally serves to pull the block carried by the jaw downwardly against the arm so that the door will be held immovable. However, it 110 is apparent that anyone desiring to open the

door by turning the knob will operate the lever to move the jaw upwardly and lift the block away from the arm so that the door may be opened or closed. The block secured to the shelf is disposed beneath the arm so that in opening or closing the door the arm travels between the blocks.

I claim:

1. A door fastener comprising a bracket, means for securing said bracket at the top of a door, a shelf formed on said bracket, upwardly extending flanges formed on said shelf, a jaw, downwardly extending flanges formed thereon, means engaging said flanges for pivotally mounting said jaw on said shelf, a semi-circular arm secured adjacent said door and disposed between the open end of said jaw and said shelf, spring means for normally securing said jaw to said arm, a lever having one end carried between said jaw and said shelf and means connecting the other end of said lever to the door knob.
2. A door fastener comprising a bracket, means for securing said bracket at the top of a door, a shelf formed on said bracket, upwardly extending flanges formed on said shelf, a jaw, downwardly extending flanges formed thereon, means engaging said flanges for pivotally mounting said jaw on said shelf, a semi-circular arm secured adjacent said door and disposed between the open end of said jaw and said shelf, spring means for normally securing said jaw to said arm, a lever having one end disposed between said jaw and said shelf, and having an upwardly inclined crook engaging said jaw and means connecting the other end of said lever to the door knob as and for the purposes set forth.
3. A door fastener comprising a bracket, means for securing said bracket at the top of a door, a shelf formed on said bracket, upwardly extending flanges formed on said shelf, a jaw, downwardly extending flanges formed thereon, means engaging said flanges for pivotally mounting said jaw on said

shelf, a semicircular arm secured adjacent said door and disposed between the open end of said jaw and said shelf, friction blocks secured to said jaw and said shelf and arranged to engage opposite sides of said arm, spring means for normally securing said jaw to said arm, a lever having one end disposed between said jaw and said shelf, and having an upwardly inclined crook engaging said jaw and means connecting the other end of said lever to the door knob as and for the purposes set forth.

4. A door fastener comprising a bracket, means for securing the same to a door, a shelf formed on said bracket, a jaw pivotally mounted at one end on said shelf, a semi-circular arm secured to the door frame and disposed between the open end of said jaw and said shelf, resilient means for normally closing the jaw upon the arm and means whereby to release said jaw from said arm.

5. A door fastener comprising a bracket, means for securing the same to a door, a shelf formed on said bracket, a jaw pivotally mounted at one end on said shelf, a semi-circular arm secured to the door frame and disposed between the open end of said jaw and said shelf, resilient closing means for the jaw and a lever pivotally mounted on said shelf and operatively arranged for releasing said jaw.

6. A door fastener comprising a bracket, means for securing the same to a door, a shelf formed on said bracket, a jaw pivotally mounted at one end on said shelf, a semi-circular arm secured to the door frame and disposed between the open end of said jaw and said shelf, resilient closing means for the jaw and a lever having one end extending transversely between the shelf and the jaw and provided with an offset arranged for opening said jaw and its opposite end operatively connected to the door knob.

In testimony whereof I affix my signature.

HALVOR E. ANDERSON.
